UNITED STATES PATENT OFFICE

101,576

DESIGN FOR A REMOTE CONTROL SELECTOR CASING

Lloyd J. Andres, Chicago, Ill., assignor to Automatic Musical Instrument Company, Grand Rapids, Mich., a corporation of Michigan

Application May 27, 1936, Serial No. 62,869

Term of patent 7 years

To all whom it may concern:

Be it known that I, Lloyd J. Andres, a citizen of the United States and resident of Chicago, in the county of Cook and State of Illinois, have invented a new, original, and ornamental Design for Remote Control Selector Casing, of which the following is a specification, reference being had to the accompanying drawing, forming part thereof.

The figure is a perspective view of the remote control selector casing showing my new design.

Both side edges are similar and the back is plain.

I claim:

The ornamental design for a remote control selector casing as shown and described.

LLOYD J. ANDRES.
